US00D983755S

(12) **United States Design Patent** (10) **Patent No.:** **US D983,755 S**
(45) **Date of Patent:** **** Apr. 18, 2023**

(54) **FLEXIBLE TROUGH**

- (71) Applicant: **Telect, Inc.**, Liberty Lake, WA (US)
(72) Inventors: **Bryan Joseph Kioski**, Spokane, WA (US); **Walter Dean Takasaki**, Spokane Valley, WA (US)
(73) Assignee: **Telect, Inc.**, Liberty Lake, WA (US)
(**) Term: **15 Years**
(21) Appl. No.: **29/782,910**
(22) Filed: **May 10, 2021**

(57) **CLAIM**

The ornamental design for a flexible trough, as shown and described.

DESCRIPTION

FIG. 1 is a front perspective view of a flexible trough with a gate on the front of the flexible trough in a closed position; FIG. 2 is a front view thereof; FIG. 3 is a back view thereof; FIG. 4 is a left-side view thereof; FIG. 5 is a right-side view thereof; FIG. 6 is a top view thereof; FIG. 7 is a bottom view thereof; FIG. 8 is a front perspective view of the flexible trough with the gate on the front of the flexible trough in an opened position; FIG. 9 is a front view thereof; FIG. 10 is a back view thereof; FIG. 11 is a left-side view thereof; FIG. 12 is a right-side view thereof; FIG. 13 is a top view thereof; and, FIG. 14 is a bottom view thereof.
The dashed broken lines depict portions of the flexible trough that form no part of the claimed design.

1 Claim, 14 Drawing Sheets
